UNITED STATES PATENT OFFICE.

GEORGE H. BABCOCK, OF PLAINFIELD, NEW JERSEY.

DESIGN FOR A ROOFING-TILE.

SPECIFICATION forming part of Design No. 20,406, dated December 16, 1890.

Application filed October 28, 1890. Serial No. 369,618. Term of patent 14 years.

To all whom it may concern:

- Be it known that I, GEORGE H. BABCOCK, a citizen of the United States, residing in Plainfield, in the county of Union and State of New Jersey, have invented and produced a new and original Design for Roofing or Sheathing Tiles, of which the following is a specification, reference being had to the accompanying drawings, forming a part thereof.
- 10 The design relates to a clay or other tile in which the ornamental effects are produced by the outline of the tile, by the surface ornamentation thereof, and by the conjunction of the two.
- 15 The design consists of a tile tending to a diamond shape, the lower sides of which are each composed of a series of convex and concave curves, which unite by a convex and concave curve in a point turned to one side 20 out of its natural conformation. The surface ornamentation consists of a leaf in conventional form, the surface of which is composed of a number of irregular undulations with a central raised stem and its branches extending nearly the length of the tile.
- 25 In the accompanying illustrations, Figure 1 illustrates a face view of the new design; Fig. 2, an edge view thereof; Fig. 3, a transverse section on the line 3 3 of Fig. 1; Fig. 4, a diagonal section on the line 4 4 of Fig. 1.

The design relates particularly to the exposed or lower face of a tile, its upper portion partaking of various shapes.

As illustrated, the tile in the main is of dia-

mond form, bearing upon its upper two sides 35 upper flanges *a b*. The other two sides of the tile are made up of a series of convex and concave curves, which unite at the lower end of the tile by a concave and convex curve in a point *c*, that is turned to one side of the natural diamond contour. The surface of the tile for a short distance inwardly from the flanges *a b* is substantially flat, and then merges into a number of irregular undulations *e f g*, extending downward to both of the lower sides 45 of the tile. With these irregular undulations there is combined a longitudinally-arranged bead or stem *h*, extending from a point near the upper portion of the tile surface downward in a graceful curve toward the lower 50 point thereof. This central bead or stem is provided with a number of branching stems *i*, also of bead form, which extend in opposite and alternate directions toward the lower sides of the tile. The whole effect produced 55 by this ornamental surface is that of a leaf, the undulating surface of which produces a variety of shades.

What is claimed is—

The design for a tile, substantially as described and shown.

In witness whereof I have hereunto set my hand, this 2d day of October, A. D. 1890, in presence of two witnesses.

GEO. H. BABCOCK.
